UNITED STATES PATENT OFFICE.

CHARLES E. HOLCOMB, OF CHICAGO, ILLINOIS.

LEGGING.

Application filed August 1, 1927. Serial No. 209,658.

My invention relates to leggings of the type primarily designed for use in and about foundries and the like to protect the legs and feet of molders during their exposure to intense heat and molten metal; the legging being adapted to provide protection against burns resulting from the spilling of the molten metal.

The invention has for its object the provision of a legging wherein the use of a steel frame throughout the front portion is eliminated, while at the same time presenting a legging which will present a comparatively smooth outer surface and which will not have a tendency to sag and wrinkle.

The invention also involves certain other specific improvements which enable the legging to be easily applied and permit it to be quickly removed.

It is essential in leggings of this general type that no exposed steel frames be employed because of their tendency to transfer heat in certain uses and hence the possibility of causing burns. Furthermore, leggings reinforced throughout with steel frames have also been found to be uncomfortable to many users. My improved constructions as herein presented obviate the necessity for such frames while at the same time being free of any tendency to sag on the leg of the wearer.

It is also essential that leggings of this type be secured in place by means which not only enables easy application of the legging to the leg, but which permits a quick release or manipulation of the fastening means when occasion requires; this object being attained by fastening means adjacent the top and bottom of the legging.

The above enumerated objects and advantages, as well as other advantages inherent in the invention, will all be readily comprehended from the detailed description of the accompanying drawings, wherein:

Figure 1 is a perspective view illustrating the application of my improved legging to a leg and foot.

Figure 2 is a side elevation of a portion of the top or upper end of the legging illustrating the top fastening means employed in Figure 1.

Figure 3 is a similar view of a portion of the lower end, with portions broken away, showing the lower fastening means.

Figure 4 is a detail sectional view taken on the line 4—4 of Figure 1.

Figure 5 is a vertical sectional view taken on the line 5—5 of Figure 3, looking in the direction of the arrows.

Figure 6 is an elevation of a closed legging, with an intermediate portion broken away and illustrating a modified form.

Figure 7 is a sectional view taken on the line 7—7 of Figure 6.

Figure 8 is a detail perspective view of a portion of the lower inside of the legging, illustrating the fastening element employed in the leggings shown in Figures 1 and 6.

Figure 9 is an elevation of the lower portion of a legging showing a modification of the fastening means.

Figure 10 is a perspective view of the fastening means employed in Figure 9, with portions broken away and shown in section.

Figure 11 is a detail perspective view of a modification of the lower fastening.

My improved legging is made of suitable flexible material, preferably of fire resisting quality, such as asbestos cloth or fire-proofed duck cut to fit about the leg below the knee and of size to permit the sides to lap each other when in place so as to completely encase the leg as shown in Figure 1, where the body 15 of the legging is shown formed by a single sheet.

My invention involves suitable means for fastening the lapped sides, both at the top and at the bottom of the legging. The legging and the fastening means employed in the construction shown in the first five figures of the drawings, comprises the main body portion 15 cut to suitable size and length; with one of the sides, namely the side which is intended to lap to the outside of the legging, provided with a vertical stiffener or stay 16 preferably consisting of a strip of sheet metal, inserted in the vertical pocket formed by lapping the material of which the legging is made and stitching the same in place as shown at 17. The metal stay 16 may extend through the vertical width of the legging and is held in place by suitable rivets, as for example rivets 18, which are disposed through the fabric and the stay, see Figures 3 and 5. The rivets 18 are also employed to secure a fastening tongue or element 19 in place. The tongue 19 preferably consists of a strip of sheet metal bent at an intermediate point as shown at 20 in Figure 5, in order that the lower unattached end may be disposed sufficiently

away from the side of the legging to which

it is attached to enable it to be easily inserted in the tongue receiving portions on the other side of the legging and also to provide sufficient space to receive the seamed edge of said side when the legging is placed about the leg. The shape of the tongue 19 and its method of fastening is clearly shown in Figure 8.

In the exemplification of the invention as shown in Figures 1 to 5, the tongue receiving portions consist of a strip of sheet metal 21, of suitable length and bent to preferably provide a plurality of tongue receiving loops 22; the strip being suitably secured on the outer face of the underlapping side of the legging, as for example by the rivets 23 at the end of the strip and intermediate of the loops, see Figure 3. It will be understood that the fastener tongue 19 is secured on the inner face of the over-lapping side of the legging, so that the free end of the tongue 19 may be readily inserted into the desired loop 22 by forcing the tongue downwardly into the loop which will provide the desired snug fit of the legging about the ankle and lower part of the leg.

Instead of employing the metal strip 21 shown in Figure 3, the legging adjacent to the bottom of its underlapping side may be provided with a strip of leather or suitable fabric as shown at 24 in Figure 6, secured to the legging, by rivets 23 or other suitable fastening means, so as to provide one or more tongue receiving loops. The tongue of the legging shown in Figure 6 is similar to the tongue shown in Figures 3 and 8 and provides a fastening for the bottom of the legging which may not only be easily made by forcing the tongue into the desired loop but which can be very quickly undone or released by a short upward pull on the side of the legging to which the tongue is secured.

The upper end of the side of the legging having the reinforcing stay 16 is shown provided with a flexible tongue 25, of leather or other suitable strong fabric; the tongue 25 being shown secured in place by rivets 26, which also extend through the upper end of the reinforcing stay 16. The tongue 25, at an intermediate point sufficiently removed from its free end, is provided with a slit 27, which is adapted to receive the tongue 28 of a well known type of snap buckle which is suitably secured to one end of strap 29; the other end of the strap 29 being held by the tongue of an ordinary buckle 30. The buckle 30 is suitably secured to the legging to enable easy manipulation; it being understood that the buckle 30 is secured to what may be termed the underlapping side of the legging, but at a suitable distance removed from the normal lapping portions of the legging.

It is apparent from the construction

shown, that the upper end of the legging may easily be fastened in place and, what is more essential, can be very quickly released by simply grasping the outer free end of tongue 25 and jerking the same toward the attached end thereof. Upon pulling the free end of tongue 25 outwardly from the legging and toward the secured end of the tongue will cause the snap-buckle tongue 28 to swing outwardly to the opposite side of its pivotal point and allow the tongue 25 to slip off tongue 28 and hence completely releasing the legging so that upward pull on the reinforced side of the legging will release tongue 19 at the bottom from its pocket or loop. With the use of strap 29 and buckle 30, the snap-buckle 28 is adjustably positioned relative to the other side of the legging provided with tongue 25, and my improved legging made to suit varying conditions and consequently obviating the necessity of manufacturing various sized leggings.

The portion of the legging which is adapted to extend about the front of the leg and at the bottom thereof is provided with a vamp or foot covering flare 31 which is shown preferably stitched in place, although it may be made integral with the body of the legging if desired. This vamp or foot-flare 31 may be provided on its inside with a flexible stiffener shown in dotted lines at 32 in Figure 1. This stiffener strip preferably consists of a strip of leather stapled in place as shown at 33. The stiffener 32 will cause the vamp or flare 31 to remain in close contact with the shoe of the wearer and prevent the flare from curling or creeping upwardly while the legging is in use.

In Figure 6 I illustrate a modification of the fastening means for the top of the legging, which consists of the snap-buckle 28, like in Figure 1, secured to a strap 29 held adjustably in place by buckle 30 like in the previously described construction.

In this construction, I provide a metal loop 34 yieldingly held in place by the looped fabric material 35 which may be secured to the legging by stitching or by a rivet as shown at 36. The free end of the metal loop 34 is provided with a finger grasping tab 37 of suitable material; and the tongue 28 of the snap-buckle passes through the metal loop 34. It is apparent that this fastening means, like that in Figure 1, may be easily made and as quickly released by simply pulling the tab 37 outwardly and toward the loop 34.

Instead of employing the fastening strip or metallic tongue 19 at the bottom of the legging, a fastening of the lower end of the legging may be accomplished as shown in Figures 9 and 10, where one side of the legging is provided with the vertical stay 16 secured between the lapped material and

held in place by rivets or in any other suitable manner. The portion of the lapped material on the inside, adjacent to the bottom of the legging is cut away as shown at 5 38 in Figure 10, so as to uncover the lower end of the metal stay 16; the stay being covered by the legging on the outer side as shown at 39.

This lower end of the stay 16 constitutes 10 the fastening tongue for the bottom of the legging and is intended to be inserted through any one of the plurality of reinforced slits 40 disposed transversely along the bottom of the underlapping side of the 15 legging.

In applying the legging, it is wrapped about the leg and the tongue 19, in the constructions shown in Figures 1 and 6, forced 20 downwardly through the proper loop members 21 or 24, or the free lower end of stay 16, in the construction shown in Figure 8, forced through the proper slit 40. The top 25 of the legging is then fastened in place by inserting the tongue of the snap-buckle 28 through the slit 27 of tongue 25 or through the metal loop 34 and then moving snap-buckle tongue 28 rearwardly as shown. If the legging does not sufficiently snugly fit the leg, strap 29 is shortened by means of 30 buckle 30; such adjustment of the fastening means need merely be made during the first fitting of the legging.

As is apparent from the drawings, the finger-grasping portion of the top fastening 35 means lies beneath the tongue of the snap-buckle when in closed position, with the result that an outward movement of the finger-grasping tongue or portion automatically causes the snap-buckle tongue to move 40 into releasing or open position.

In Figure 11 I show a modification of the bottom tongue receiving means consisting of a strap 41 secured to the outer face of the inner or lapped side of the legging, preferably by means of rivets as at 42, spaced apart so as to hold the strap in the transverse position shown. The short end of the strap is provided with the usual buckle 43; while the long end is provided with a series 50 of buckle-tongue receiving holes 44. As is apparent, the strap 41 provides an adjustable loop to receive either the tongue 19 or the tongue forming end of stay 16; the strap permitting the lower end of the legging to 55 be adjusted to variations in the legs of wearers.

The exemplifications are believed to be the best embodiments of the invention, but modifications may be made without, however, departing from the spirit of my invention.

What I claim is:—

1. A legging comprising a leg covering portion of flexible sheet material formed to permit the two sides to lap each other, the 60 outer lapping side being folded upon itself

to provide a vertically disposed pocket, a vertical stay secured within said pocket, an adjustable strap secured to one side of the legging adjacent to the top thereof so as to extend transversely, the outer end of said 70 strap being provided with a snap-buckle, a snap-buckle tongue receiving portion secured to the other lapping side of the legging in substantial alignment with said strap, said tongue receiving portion terminating in 75 a finger-grasping portion, a vertically disposed tongue at the lower end of the legging arranged on one of the lapping sides so as to be completely covered thereby, and transversely disposed means at the lower end of 80 the other lapping side to receive said tongue, said means permitting adjustment to different leg thicknesses.

2. A legging comprising a leg covering portion formed to permit lapping of the 85 sides, a strip of stiff material secured at its upper end adjacent to the lower end of one of said sides and disposed vertically with the lower free end spaced from the legging to provide a fastening tongue, said tongue 90 being disposed on the inner side of the outer lapping side, tongue receiving means disposed transversely at the bottom of the other side of the legging, said means permitting adjustment to various leg thicknesses and 95 adjustable means for securing the upper end of the legging in place.

3. In a legging of the character described, a leg covering portion of flexible protective material formed to permit the sides to lap each other, a stay secured vertically in the outer lapping side, a rigid strip on the inner side of said side disposed vertically adjacent to the bottom of the legging, said strip being bent intermediate of its ends to have 100 the lower end thereof spaced from said legging side, means whereby the upper end of said strip and stay are secured to the legging, and laterally spaced portions on the inner lapping side for receiving the lower 105 end of said strip.

4. A legging comprising a leg covering portion formed to have lapping sides, a snap-buckle secured to one of said sides adjacent to the top, a finger-grasp secured to the 110 other lapping side and formed to receive the snap-buckle tongue, a vertically disposed rigid element at the bottom of and located wholly within one of said sides, and means at the bottom of the other side for engagement with said element.

5. A legging composed of flexible protective material formed to have the sides lap each other when wrapped about the leg of a wearer, the forward lower end of the legging being provided with a vamp or flare adapted to extend across the front of the shoe of the wearer, vertically disposed stiffener means secured on the inner surface of 115 said flare, adjustable fastening means for 120

the upper end of the legging involving a snap-buckle attached to one side of the legging so as to have the tongue of said snap-buckle extend horizontally, flexible snap-buckle tongue receiving means secured to the other side of the legging with the free end of said means arranged to underlie said snap-buckle tongue and constitute a finger-

grasp adapted to move said tongue into releasing position, a vertically disposed rigid tongue on one of the sides adjacent to the bottom of the legging, and tongue receiving portions on the other side of the legging arranged transversely at a point normally above the free end of said rigid tongue.

CHARLES R. HOLCOMB.
